UNITED STATES PATENT OFFICE.

WILLIAM R. MCGIBONY, OF MONROE, GEORGIA.

RAILROAD-SWITCH.

SPECIFICATION forming part of Letters Patent No. 451,507, dated May 5, 1891.

Application filed December 17, 1890. Serial No. 375,025. (No model.)

To all whom it may concern:

Be it known that I, WILLIAM R. MCGIBONY, a citizen of the United States, residing at Monroe, in the county of Walton and State of Georgia, have invented a new and useful Railroad-Switch, of which the following is a specification.

This invention relates to railroad-switches, and more especially to that class of switches in which a pivoted frog-plate is operated automatically simultaneously with the switch-rails.

The invention consists in the improved construction and combination of parts, which will be hereinafter fully described, and particularly pointed out in the claims.

In the drawings hereto annexed, Figure 1 is a plan view of a railroad-switch constructed in accordance with my invention. Fig. 2 is a perspective detail view of a pivoted frog and its supporting-plate. Fig. 3 is a transverse sectional view of the frog and the supporting-plate, taken on the line 3 3 in Fig. 1. Fig. 4 is a detail plan view of the frog removed from its supporting-plate.

Like numerals of reference indicate like parts in all the figures.

1 1 designate the main-line rails, 2 2 the siding-rails, and 3 3 the pivoted switch-rails, which are connected in the usual manner by the bridle-bars 4. At the junction of the inner main-line rail with the inner siding-rail is arranged a supporting-plate 5, upon which is mounted the pivoted frog 6. The latter is provided at its sides with longitudinal laterally-extending flanges 7 and the supporting-plate on its upper side with longitudinal undercut flanges 8, adapted to form seats for the flanges 7 of the frog. The pivoted end of the latter is rounded, and the side flanges 7 are extended partially around the heel end, so as to be permanently seated in the undercut flanges of the supporting-plate. Suitable supports are provided adjacent to the top for a pair of T-shaped levers 9 9, the arms of which are connected by the rods 10 10. The later-

ally-extending arm of one of said levers is connected by a rod 11 with one of the pivoted switch-rails, and a rod 12 connects the laterally-extending arm of the other lever with the pivoted frog. It will thus be seen that when the switch-rails are adjusted the pivoted frog will be simultaneously thrown into position to open the main line or the siding, as the case may be.

The supporting-plate 5 is provided with a spacing-block 15, having undercut recesses 16 to receive the ends of the rails 1 2 and to prevent said rails from being forced together.

Having thus described my invention, what I claim is—

1. In a railroad-switch of the class herein described, the combination, with the supporting-plate having longitudinal undercut flanges, of the pivoted frog having longitudinal laterally-extending flanges adapted to engage the flanges of the supporting-plate, said pivoted frog being provided with a rounded and partially-flanged heel permanently seated in the undercut flanges of the supporting-plate, substantially as and for the purpose set forth.

2. In a railroad-switch of the class herein described, the combination, with the supporting-plate having longitudinal undercut flanges and a spacing-block 15, provided with undercut recesses 16, of the pivoted frog having longitudinal laterally-extending flanges adapted to engage the flanges of the supporting-plate, said pivoted frog being provided with a rounded and partially-flanged heel permanently seated in the undercut flanges of the supporting-plate, and the rails 1 2, substantially as set forth.

In testimony that I claim the foregoing as my own I have hereto affixed my signature in presence of two witnesses.

WILLIAM R. MCGIBONY.

Witnesses:

R. A. COOK,
JOHN P. EDWARDS.
